UNITED STATES PATENT OFFICE.

LYMAN L. DENNICK, OF LOS ANGELES, CALIFORNIA.

INDEX.

No. 914,556.

Specification of Letters Patent.

Patented March 9, 1909.

Application filed June 15, 1908. Serial No. 438,690.

To all whom it may concern:

Be it known that I, LYMAN L. DENNICK, a citizen of the United States, and resident of Los Angeles, in the county of Los Angeles and State of California, have invented a new and useful Improvement in Indexes, of which the following is a specification.

My invention relates to indexing and contemplates a plan or system which includes 10 a chart or charts as well as one or more books or receptacles to be used therewith.

In places where many names are to be arranged or classified for future reference it is necessary that the plan or system employed be as well adapted to the entry or 15 cataloguing of the names or subject matter by the indexer as to facilitate the finding of it by the searches. It is also necessary that means be provided for the overflow or for 20 the occasional increase or multiplicity of some particular name over what is usually the case and for what it was thought ample provision had been made, when the index was prepared, as well as to provide for 25 miscellaneous names, or those not adapted to be classified under any general heading. It is also desirable that means be provided by which the indexer, or one having charge 30 of the books or indexes, can give the desired information as to the book and page on which the desired name or subject matter can readily be found by any one even though they should not be versed in making 35 searches.

One object therefore, of the invention, is 35 to provide a book in which certain leaves or pages are grouped or set aside for containing all the names or subjects commencing with a certain letter or letters of the alphabet, as the surnames of individuals; and 40 then providing a sub-index or chart, as a smaller leaf, for each set or group of said pages for indicating on which one or more of them a subdivision or smaller group of 45 the names can be found, as those having Christian names commencing with the same initial or letter of the alphabet. Each group of leaves or pages is of the same size or number but the page numbers of all of them are 50 not originally indicated on the particular chart or sub-index for that group, but are adapted to be placed thereon, if desired, when said extra leaves or pages have been used.

Another object is to provide means, as a 55 larger leaf or chart, on which the divisions

or subdivisions of all of the books of a series of books is printed and by means of which any particular name, if it appears at all, can be quickly found in any book of the 60 series.

The accompanying drawings illustrate the invention and form a part of the specification.

Figure 1 is a plan view of an open book 65 embodying one part of my invention. Figs. 2 and 3 are each a broken plan view of a portion of the same. Fig. 4 represents a series of index books belonging to and forming a part of my system of indexing. Fig. 70 5 is a perspective of a chart book, open to show the extra pages.

Referring more particularly to the drawings: 1 indicates a book which may be of any desired size and has its leaves divided 75 into spaces 2 by the usual vertical and horizontal lines 3. The leaves are numbered or indicated consecutively in the usual manner and are preferably provided with suitable headings 4, as "Grantor, Grantee", &c. 80 when the index is to be used for deed records, and "Mortgagor, Mortgagee" &c., when it is to be used for a record of mortgages. When the index is to be used for the names of persons or individuals, as in the 85 present instance, the leaves are divided into groups, preferably of 16 pages each, and the groups are given indicators as letters of the alphabet, which are placed upon tabs 5, formed in any suitable manner, as by cutting 90 away the margins of part of the leaves. As my system requires about forty of these 95 groups or tabs it is impossible to place them in a single row so I make two rows of tabs with part of the letters in one row and the rest in the other row as shown in Figs. 1 and 2. To some of the groups I assign one letter, as the groups of the surnames of persons or individuals commencing with the letters "A", "F" or "N", as indicated at 6, 100 while to other letters are assigned three or more groups, as "B", "H", "M", and "S", as indicated at 7, and other letters which are used less frequently, as "I" and "Q", are placed upon tabs with other letters, as "J" and "P" respectively, as at 8, 105 while yet other letters as "U", "V", "X" and "Y", are all placed upon a single tab as at 9. Each of the initial letters stands alone upon the tabs or combined with other initial letters, but many of them are placed on two or more tabs, and followed by an 110

other letter to indicate the second letter of the name, as for instance, "B" is used on four tabs, once alone, and three times it is followed by the letters "a", "e" and "r", 5 respectively, thus causing these groups to read "Ba", "Be", "Br", and "B", respectively, as indicated at 10. In this manner more space is given to the names which occur more frequently and they are also 10 divided into smaller groupings to facilitate the locating of the particular page upon which any one of the surnames commencing with this particular initial can be more readily indexed or found, as the case may 15 be. In addition to this the greatest economy of space in the number of groups of leaves is secured and the size of the book is reduced to the minimum consistent with ease and facility of working the index. Located upon 20 the first page of each group is a smaller un-paged leaf 11, upon which are placed letters indicating the initials of the Christian names and also corporations, as banks, firms, companies, &c. These initials are 25 divided into groups as indicated at 12, and are placed in a vertical row or column, some of the letters standing alone and others standing in a row of two or more letters. These lines or groups of letters are followed by a 30 column of Figs. 13 which indicate the particular pages of that group on which the names to be indexed are to be placed or sought for, as the case may be. For instance, Fig. 1 of the drawings shows a book 35 opened with the page 16 at the left hand and 17 at the right and the un-paged leaf 11 covering part of page 17. Referring to the leaf 11 it will be noticed that the letters "A" and "B" stand opposite the number 16, 40 which indicates that all surnames commencing with the letters "Ba" (which appears on the tab of the group of leaves commencing with page 17) and having Christian names commencing with either of the initials "A" or "B" will be found on page 16, 45 as "Andrew Baker", "Belle Bailey", &c. The letter "C" is followed by 17 which indicates that the surnames commencing with "Ba" and having Christian names com- 50 mencing with the initial letter "C" will be found upon page 17, as "Charles Baker", &c. In the same manner each Christian name of that particular group of surnames can be properly paged or indicated by the 55 index letters on the un-paged or sub-index leaf, but as some of the Christian names beginning with certain letters occur more frequently than others it is necessary to provide more pages in each group for such par- 60 ticular names. For instance, as the names beginning with "J", as "John", "James", &c., occur very frequently I have given that letter three pages 21, 22 and 23 while such a letter as "C" only needs one. On the other 65 hand the Christian names beginning with

such letters as "O", "P", "Q", and "R", "G", "T", "U", "V", and "W", "X", "Y", and "Z" occur very infrequently and each of said three groups of four letters is followed by one number, as 26, 27, and 28, 70 respectively, which indicates that Christian names commencing with either letter of each group will be found upon the particular page indicated by the number following that row or group of letters. In addition to 75 these initial letters for Christian names space is provided on each sub-index for the insertion of special names or titles as "Bank of Los Angeles", "Bankers Trust Company".

As it is impossible to correctly provide the exact amount of space required for indexing the thousands of names that it is desired to place in a single volume and as it would tend to confusion and loss of time both in indexing and in searching to place the surplus names promiscuously upon a group of leaves at the end of the volume, as is frequently done, each group of my index is provided with enough extra pages 14, in addition to 80 the regular pages 15 for each group, (these pages 14 being marked extra in Fig. 5) to contain the surplus or overflow of names from that group thereby greatly economizing space and also rendering the index much 85 more convenient by locating the surplus leaves 15 directly adjacent to the principal leaves and also by permitting the names commencing with the same initial letters to be kept separate and apart from those com- 90 mencing with other initial letters. For instance, in the paging of my index, which I have shown and which I prefer, there are three extra pages to each group except the first group which has only two pages upon 95 which extra names belonging to that particular group may be placed. This variation of one page is caused by utilizing the last page of the preceding group, which is the left hand page when the book is open, 100 for the insertion of names belonging to the following group, except the first group which has no preceding group or page.

In Fig. 3 the column of figures 13 on the sub-index 11 runs from 1 to 13, which indicates that all of the surnames commencing with the letter "A" and having a Christian name commencing with any letter of the alphabet, as the letters of each sub-index runs from "A" to "Z", can be written upon 115 said thirteen pages, while the surplus names from this group can be written on pages 14 and 15, but as shown by Fig. 1 the last page of group "A" is 16, and it is utilized as the first page of the "Ba" group, whose sub-index thus runs from 16 to 28 inclusive, 120 which makes thirteen pages for that group. As the "Be" group would open between pages 31 and 32, or three numbers above 28, this gives three extra pages for the Chris- 125 130

tian names belonging to the "Ba" group instead of only two extra pages as above described for the first or "A" group. In addition to these extra pages for each group I provide enough other extra leaves or pages indicated at 16 and marked 2d extra in Fig. 5 to afford room for all of the miscellaneous names that may occur throughout all of the different groups, one or more of the 2d extra sets being provided at a suitable place or places in the book, following a series of the groups above referred to, to provide for overflow from any part of the series of groups. For instance, in Fig. 1 the name "Bank of Los Angeles" on the sub-index 11 is followed by the number 302, which indicates that that name will be found upon page 302 of the 2d extra group 16 of the index, said page 302 being the first page following the group on the last tab in the first row of tabs and its three extra pages. The name "Bankers Loan Company" is followed by number 304, which indicates that that name will be found indexed upon page 304. In this manner the entire list of miscellaneous names occurring throughout the various groups of surnames down to and including the letter L can be placed upon the group of extra leaves following said group "L" and indicated by the number that follows each of said miscellaneous names, said numbers being written upon the index at the time of making the entry, whereas all of the regular names, or those having Christian names with some letter of the alphabet, are printed upon the sub-index. To facilitate finding the particular page to which these surplus and miscellaneous names are carried I have provided at the bottom of each page of the index an appropriate notice, upon which the number of the extended page can be placed, as, for instance, "See page 29" at the bottom of page 16 in Fig. 1, which indicates that the extra surnames belonging to the original page and having Christian names beginning with "A" or "B" will be found on page 29.

As above described it will be seen that any index book can be made comprehensive enough to receive the names that will prob-

ably be written therein, and at the same time the names will be so classified, first, by grouping the surnames commencing with certain initials, and then subdividing such groups or divisions according to the Christian names commencing with certain letters, as will enable the indexer to quickly and correctly locate the particular page upon which any given name must be written, thereby eliminating the possibility of error or mistake, and also guiding the searcher quickly and accurately to the place in which the name must be found if it occurs in the book.

It sometimes happens that in making subdivisions of land that the same name will be used a great many times, especially as grantor, in which case one or more pages for the miscellaneous names or titles can be set aside for that name, which will facilitate the work of indexing and of searching.

Having described my invention I claim—

An index book having its leaves numbered consecutively and divided into groups, each group having its first leaf provided with a tab, letters of the alphabet arranged on said tabs, a smaller leaf arranged at the inner edge of each of said first leaves and provided with all of the letters of the alphabet arranged in vertical rows, said last mentioned letters corresponding with the initial letters of the given or Christian name to be indexed, the arrangement of said letters on all of the smaller leaves being duplicates, numbers on each of said smaller leaves in horizontal alinement with said letters, said numbers being duplicates of certain of the page numbers of the group of leaves of which said first leaf forms a part, a plurality of extra leaves for each group of leaves containing the numbers of the remaining pages of said group, and a greater number of extra leaves at the end of a plurality of groups.

In testimony whereof, I have hereunto set my hand at Los Angeles, California, this 8th day of June, 1908.

LYMAN L. DENNICK.

In presence of—

G. F. HACKLEY,
FRANK L. A. GRAHAM.
